(57) **CLAIM**

We claim the ornamental design for a dispenser, as shown and described.

DESCRIPTION

This application is related to U.S. Des. Pat. App. Ser. No. 29/645,495, filed on Apr. 26, 2018, entitled “Faucet and Soap Dispenser Configuration,” which is incorporated herein by reference in its entirety.

FIG. 1 is a front, right, perspective view of the dispenser; FIG. 2 is a front side view of the claimed design of FIG. 1; FIG. 3 is a rear side view of the claimed design of FIG. 1; FIG. 4 is a right side view of the claimed design of FIG. 1; FIG. 5 is a left side view of the claimed design of FIG. 1; FIG. 6 is a top view of the claimed design of FIG. 1; and, FIG. 7 is a bottom view of the claimed design of FIG. 1. The ornamental design which is claimed is shown in solid lines in the drawings. The evenly dashed broken lines illustrate portions of the dispenser that form no part of the claim. Broken lines formed of unequal length dashes (i.e., dash-dot) show boundaries between claimed and unclaimed portions of the design.
